UNITED STATES PATENT OFFICE.

JOSEPH S. BEAN, OF SHARON, VERMONT.

RAIL-FASTENER.

1,149,888.

Specification of Letters Patent. Patented Aug. 10, 1915.

Application filed May 1, 1915. Serial No. 25,195.

To all whom it may concern:

Be it known that I, JOSEPH S. BEAN, a citizen of the United States of America, and resident of Sharon, in the county of Windsor and State of Vermont, have invented 5 certain new and useful Improvements in Rail-Fasteners, of which the following is a specification.

This invention relates to railway tracks and particularly to rails and rail fasteners.

An object of this invention is to provide 10 novel means for attaching rails to cross ties of tracks, whereby the said rails may be securely held in place so long as the fastenings 15 are intact, the said fastenings being readily detachable for the purpose of dismantling the track or for removing rails to renew those which become impaired through use or accident.

20 A further object of this invention is to provide a rail having a tapered body and corrugated or roughened head or tread surface designed to increase the frictional contact between the wheels of the car and the 25 rails, the said taper of the rails extending from the base to the head so that the base is relatively wider than the head and produces a firm bearing on the cross ties.

With the foregoing and other objects in 30 view, the invention consists in the details of construction, and in the arrangement and combination of parts to be hereinafter more fully set forth and claimed.

In describing the invention in detail, reference will be had to the accompanying 35 drawings forming part of this specification wherein like characters denote corresponding parts in the several views, and in which—

40 Figure 1 illustrates a longitudinal sectional view of a rail with a coupler applied to one end thereof; Fig. 2 illustrates a top plan view of a fragment of the rail; Fig. 3 illustrates a sectional view on the line 3—3 45 of Fig. 1; Fig. 4 illustrates a sectional view on the line 4—4 of Fig. 1; and Fig. 5 illustrates a perspective view of a coupling block.

In these drawings 7 denotes a fragment 50 of a rail, 8 a fragment of an adjacent rail, each of which has a recess in its base, the rail 7 having a recess 9 and the rail 8 having a recess 10, the said recesses being flared in width from the ends of the rails to the ends 55 of the recesses and the walls of the recesses being tapered or inclined toward each other

from the bases to the upper walls of the recesses. The upper walls of the recesses are furthermore, each provided with a cavity 11 for the reception of a head of a bolt or the 60 nut of a bolt, the bolt 12 fitting in each cavity extending through a coupling block 13 and the cross tie 14.

The coupling block 13 employed in this connection consists of a block of a configuration to fit within the recesses in the ends of the rails and obviously the said blocks must be of flared configuration from their centers to their ends and must be tapered from their bases to their tops so that they will, as stated, 65 fit within the recesses in the ends of the rails. The coupling block 13 has vertically disposed apertures 15 and transversely disposed apertures 16, the former of which are adapted to receive the bolts 12, whereas the latter are provided for the reception of the 70 cross bolts 17, which cross bolts extend through apertures 18 and 19 in the sides of the rail.

From an inspection of the drawings, it 75 will be seen that when the coupling blocks are secured to the cross ties by the bolts 12, rails having recesses in their ends may be applied to the coupling block and when the transversely disposed bolts 17 are inserted 80 through the rails and coupling blocks, the parts are in such assembled relation as to withstand unusual wear and owing to the fact that the fastenings for the coupling 85 blocks are under the rails, the cross ties 90 where they are penetrated by the bolts are protected from the weather and rapid deterioration of the cross ties is prevented.

As a means for preventing spreading of 95 rails and to aid in the anchorage thereof, each rail may be provided with a recess intermediate its length, such recess being identified by the numeral 20. The said recess is provided for the reception of a securing block 21, which securing block is attached 100 to a cross tie by a bolt 22 and as a means for anchoring the rail to the block, a cross bolt 23 is inserted in a transversely disposed aperture 24 of the anchoring block and in apertures 25 in the sides of the rail so that 105 the anchoring block taking the place of the ordinary spikes or other means for attaching the rails to cross ties, affords an anchorage which will, as stated, prevent deterioration of the cross ties, yet accomplishing the 110 purposes of securing the rails and preventing spreading thereof effectively.

As will be seen from an inspection of Fig. 2, the tread surface of the rail is provided with diagonally disposed corrugations 26, the said corrugations extending across the 5 surface at different angles so that they intersect and produce diamond shaped tread surfaces of such roughened character as to insure traction between the wheels and the surfaces of the rails.

10 I claim—

1. In a railway track, rails having upwardly tapered bodies and corrugated tread surfaces, said rails having recesses in their bases at their ends, the upper walls of the 15 recesses having cavities therein, a coupling block, means for securing the coupling block to a cross tie including bolts having their ends resting in the cavities of the rails, said coupling blocks lying in the recesses at the 20 ends of the rails and transversely disposed securing devices extending through the coupling block and rails.

2. In a railway track, rails having upwardly tapered bodies and corrugated tread 25 surfaces, said rails having recesses in their bases at their ends and intermediate their lengths, the upper walls of the recesses having cavities therein, a coupling block, means for securing the coupling block to a cross tie 30 including bolts having their ends resting in the cavities of the rails, said coupling blocks lying in the recesses at the ends of the rails, transversely disposed securing devices extending through the coupling block and rails, anchoring blocks, means for securing 35 the anchoring blocks to the cross ties, and

transversely disposed members for securing the rail to the anchoring blocks.

3. In a railway track, rails having upwardly tapered bodies, said rails having recesses at their bases at their ends and intermediate their lengths, the upper walls of the recesses having cavities therein, a coupling block, means for securing the coupling block to a cross tie, including bolts having their 40 ends resting in the cavities of the rails, said coupling blocks lying in the recesses at the ends of the rails, transversely disposed securing devices, extending through the coupling block and rails, anchoring blocks, 45 means for securing the anchoring blocks to the cross ties, and transversely disposed members for securing the rail to the anchoring blocks.

4. In a railway track, rails having upwardly tapered bodies, said rails having recesses in their bases at their ends, the upper walls of the recesses having cavities therein, a coupling block, means for securing the coupling block to a cross tie including bolts 50 having their ends resting in the cavities of the rails, said coupling blocks lying in the recesses at the ends of the rails and transversely disposed securing devices extending through the coupling block and rails. 55

In testimony whereof, I hereunto affix my signature in the presence of two witnesses.

JOSEPH S. BEAN.
